UNITED STATES PATENT OFFICE

FRITZ HUBER, OF MANNHEIM, GERMANY, ASSIGNOR TO HEINRICH LANZ AKTIEN-
GESELLSCHAFT, OF MANNHEIM, GERMANY

SPARKING DEVICE

Application filed January 9, 1931, Serial No. 507,551, and in Germany March 6, 1929, and January 2, 1930.

The present invention relates to a sparking device for starting, especially in tractors, hot bulb engines of the two-cycle type which are started by moving the flywheel several times to and fro until the necessary compression has been produced. As is generally known, it is not so important in which direction machines of this class are started. Should they start, for instance, in a direction of rotation opposite to the one desired, they are permitted to run idle until the bulb is heated to such an extent that the machine will continue working on heavy oil, whereupon the fuel is shut off until the impulse given by the flywheel becomes too weak for a complete rotation. The moment the flywheel goes back gas is given again, and the machine will move in the direction wanted.

The invention consists in starting a hot bulb engine normally running on heavy oil with light oil brought to ignition at a spark plug provided in the hot bulb and producing continuous sparks in rapid succession by means of an electric device. The electric device adapted to produce, in connection with the spark plug, continuous sparks in rapid succession may comprise a high speed magnet apparatus or a battery combined with a sparking coil, condenser, and buzzer.

If the continuous sparks are produced by means of a magnet apparatus, it may be driven directly by the flywheel of the engine in order to attain a high speed.

One embodiment of the invention is shown in the accompanying drawings, in which Figure 1 is a total view of the invention; Fig. 2, a detail view seen in the longitudinal direction of the machine; Figs. 3 and 4 are, respectively, a side and a top view of the pumps for light and heavy oil and of their drive; and Fig. 5 is a sectional view of the cylinder head.

Referring to the drawing, *a* is the tractor, *b* are the fuel pumps, *c* is the cylinder head, *d* a heavy oil nozzle, *e* a light oil nozzle, *l* the igniting unit, *b*1 the pump for heavy oil, and *b*2 the pump for light oil.

The two pumps are controlled by the lever *k* by means of which the shaft *w* can be turned. Firmly connected with the shaft *w*

are the eccentric *w*1 and the lever *w*2. The lever *w*3 is rotatably disposed on the eccentric *w*1, and the key *w*4 depends from the lever *w*2.

The pumps are driven by the eccentric *r* 55 disposed on the main shaft of the motor and moving, by means of the eccentric rod *r*1, the plunger *r*2 for the heavy oil pump *b*1 and, by means of the eccentric rod *r*3, the lever *w*3 for the plunger *r*4 of the light oil pump *b*2. 60

The key or wedge *w*4 is arranged between the plunger *r*2 and the piston *b*1 so as to increase, or reduce to zero, the stroke of the pump by raising and lowering the key *w*4. By moving the eccentric *w*1 by means of the 65 shaft *w*, the lever *w*3 can be brought into or out of engagement with the plunger *r*4 of the light oil pump *b*2.

The elements forming the groups *w* and *r* are adjusted relative to the lever *k* in such 70 a way that, according to the central or end positions of the latter, either one or the other pump or none of them is operated. The heavy oil is injected in the known manner during the first half of the compression 75 stroke at the end of which it is ignited. The light oil, however, is injected only towards the end of the compression stroke.

The igniting element often employed in similar devices is a strong helically wound 80 wire heated by accumulator current, the accumulator being supplied by a dynamo provided in the tractor. The purpose of such an arrangement is to make a small dynamo do corresponding to the power of the tractor. 85

According to the invention, the permanently glowing strong wire in this arrangement is replaced by a spark plug in order to reduce the consumption of electrical energy still more. However, normal spark plug operation is unsuited for starting heavy oil engines on light oil for the reason that the time of ignition and the timing of injecting the light oil cannot be harmonized in the same manner as in internal combustion engines 90 and lacks the requisite accuracy. In the modification shown in the drawings a high tension magnet apparatus operated at a high speed of approximately 4000 revolutions per minute is employed so as to insure a rapid 95 100

succession of sparks at the plug and absolute certainty of ignition no matter at what time the fuel is injected, i. e., the speed of the magnet outfit is a multiple of that of the crankshaft, and, during the injection period, a large number of sparks jumps over all the time while in the usual kind of spark plug ignition sparks jump over only at the moment of injection.

10 The sparks at the plug serve only for igniting the light oil to preheat the bulb, and if the bulb is sufficiently heated to be capable of igniting heavy oil, a change is made to the latter. In the modification shown a control device is provided which turns on the heavy oil pump and stops the magnet apparatus. According to Figs. 1 and 2, the magnet apparatus *m* can be rotated with its base about a fixed point *m*1 and is operated by a friction disc *m*2 when the latter rests on the flywheel *n*. With the magnet apparatus *m* a roll *m*3 is connected which rests on a cam *k*1 of the lever *k*. If the lever *k* is in the left-hand position shown in Fig. 1, the friction disc *m*2 rests on the flywheel *n* and is held thereto by the spring *m*4. If the lever *k* is pressed into the right-hand position shown in Fig. 1, it lifts off the magnet from the flywheel *n* by means of the cam *k*1. The left-hand position of the lever *k* corresponds therefore to the starting position of the light oil pump and the right-hand position, to heavy oil fuelling, so that, when starting the light oil pump, the lever *k* actuates the magnet apparatus, and stops it when the light oil pump is rendered inoperative.

Instead of a high speed magnet apparatus a battery in connection with a sparking coil, condenser, and buzzer may be employed. Being used only for the brief starting time, the battery may be small and handy so as to facilitate removal and charging at some other place or, if the vehicle having this arrangement is provided with a dynamo, it may be charged by the latter. In view of the description given above it is thought that any further explanation of the construction and operation of such a modification is unnecessary.

50 It is pointed out in particular that the well-known cell ignition in four-stroke engines has nothing to do with the present invention which relates to two-stroke engines using crude oil. In four-stroke engines, there is always an interrupter for regulating the time of ignition while, in contrast therewith, it is impossible to speak of a definite time of ignition in connection with the present invention.

60 I claim:—

1. In a two cycle heavy oil engine, means for injecting light oil during starting, a spark plug arranged for igniting the injected light oil, electric means for producing a continuous rapid succession of sparks at the

spark plug, and a single means operable to substantially simultaneously control the light oil injecting means and the electric means to render both of said means operative or both inoperative.

2. In a two cycle heavy oil engine, means for injecting light oil during starting, a spark plug adapted to ignite the injected light oil, electric means for producing a continuous rapid succession of sparks at the spark plug, means for injecting heavy oil, and a single means operable to substantially simultaneously render the light oil injecting means and electric means inoperative and to render the heavy oil injecting means operative. 75

3. In a two cycle heavy oil engine, means for injecting light oil during starting, a spark plug adapted to ignite the injected light oil, electric means for producing a continuous rapid succession of sparks at the spark plug, means for injecting heavy oil, and a single means operable upon one movement to substantially simultaneously render the light oil injecting means and electric means inoperative and to render the heavy oil injecting means operative. 85

4. In a two cycle heavy oil engine, a pump for supplying light oil to the engine for starting, a pump for supplying heavy oil to the engine, controllable driving connections for said pumps, a spark plug arranging for igniting the light oil, electric means for producing a continuous rapid succession of sparks at the spark plug, and a single means operable to substantially simultaneously interrupt the driving connections to the light oil pump and throw out said electric means and to complete the driving connections to the heavy oil pump. 95 100

In testimony whereof I have affixed my signature.

FRITZ HUBER.
